UNITED STATES PATENT OFFICE.

ARTHUR C. ARENDT, OF CLEVELAND, OHIO.

ILLUMINATED SIGN.

Application filed November 13, 1925. Serial No. 68,761.

This invention relates to signs, particularly those which are used adjacent street intersections, and has for one of its objects the provision of a sign which functions as a warning signal for traffic as well as for indicating the identity of the street adjacent such intersection. To this end, my invention contemplates the provision of a sign which may be cheaply manufactured and quickly set up at the desired location, yet which will occupy very little space at the street intersection.

A further object of my invention is to make a sign which is readily accessible for inspection or repair, and which permits the name plates to be interchanged. In this way, the complete sign except for the name plates, may be made up, and the desired plates may then be inserted. Thus, a sign may be moved from one place to another without requiring the substitution of a complete structure, or one plate may be replaced by another without requiring the replacement of the entire sign in case any damage should occur to the sign during use.

The preferred means for carrying out my invention is illustrated in the drawings, wherein Fig. 1 is a side elevation of a sign embodying my invention; Fig. 2 is a side elevation partly in section of a portion of the sign with the cover raised from the casing; Fig. 3 is a transverse section taken through the sign on a plane indicated by the line 3-3 in Fig. 1. Fig. 4 is a transverse section taken through the forward portion of the sign shown in Fig. 1, and on a plane indicated by the line 4-4 in Fig. 1; Fig. 5 is a perspective view illustrating the means for enabling the electrical connection to be made between the cover and base of the casing and Fig. 6 is a wiring diagram.

The sign made in accordance with my invention is shown as a hollow upright housing 10, which is mounted on a standard 11, the lower end of which is shown as being attached to a base 12. In practice the base is fastened to the ground, while the standard is sufficiently high to prevent the casing from being obscured by vehicles, which may be stationed along the curb near the street intersection at which the sign is situated. The casing may be illuminated from the interior while the sides may be provided with name plates to suit the location of the sign.

In the preferred form, the casing comprises a hollow box-like member having a

base 15 to which corner posts 16 are attached. Light sheet metal plates 17 may be attached to the corner plates by securing members 18 to make a four sided casing 60 which is preferably square in cross section. These plates have suitable indicia stamped therein through which light may shine in the usual way. Behind the plates, I insert translucent members in the form of glass plates 65 shown at 19. The translucent members may be held in position by guides 20 which are shown as angle pieces and as being attached to the inner sides of the plates 17. The translucent members may be thus slid vertically into position from the top of the casing when the cover is removed.

To illuminate the sign I have shown an electric lamp 30 which is mounted on the base 15 and another lamp 31 which is carried by the cover 32. These lamps may be arranged in multiple as shown in Fig. 8, wherein a source of supply is indicated at 35, and a thermostatic switch in circuit with the lamp is shown at 37. This switch as 80 illustrated in Fig. 3 is preferably mounted adjacent the bottom of the casing and is so made that normally the thermostatic switch is closed. If the main switch to the circuit is also closed, then the passage of 85 current through the thermostatic heats up such member and gradually opens the switch. The switch then remains open till the thermostat has cooled sufficiently to make another connection. In this way the lamps 90 are illuminated intermittently and the degree of such intermittent operation may be satisfactorily controlled by the adjustment of the thermostatic member. I am not concerned in this application, however, with the 95 details of construction of the thermostatic member.

To permit removal of the cover and at the same time to provide adequate electrical connections for the lamp which is carried thereby, I have shown conductors 40 which are carried adjacent two of the posts 16 within the casing, and which extend from top to bottom thereof. The upper and lower ends of the conductors are arranged to form 100 electrical connections with the socket members 41 and 42 respectively, when the sign is assembled as a complete unit. The connection at the top and bottom of the conductors therefore enables one to remove the 105 cover and with it the associated lamp to permit inspection of the sign or replacement

of the lamp. When the cover is replaced an electrical connection is automatically made between the conductors 40 and the socket members 41 whereby an electrical circuit through the lamps 30 and 31 is completed.

The particular advantage of a sign made in accordance with my invention is the fact that the name plates may be readily interchanged to suit varying conditions, and that the sign as a whole may be inexpensively constructed and quickly set up for use. Moreover the intermittent operation of the lamps attracts the attention of an observer and makes the sign adapted for use as a warning or stop signal.

I claim:

1. An illuminated sign comprising in combination, means for supporting the casing, a casing, said casing having a base, sides and cover there being two lamps within the casing, one mounted on the base and the other on the cover, a common source of electrical supply for said lamps and means for automatically effecting an electrical connection between said lamps whenever the cover is placed in operative position upon the casing.

2. An illuminated sign comprising in combination, a standard, a casing carried thereby, said casing having a base, side walls and cover, electrical conductors extending through the standard and into the casing, an electric lamp mounted upon the base within the casing, another lamp mounted upon the cover within the casing, and means carried by the casing and providing a separable connection with the base and the cover respectively for completing an electrical circuit between the conductors and lamps.

3. An illuminated sign comprising in combination, a casing, a support therefor, said casing having a base, side walls and a cover, the cover being removable, said side walls comprising interchangeable sheet metal plates, some of said plates having indicia stamped therein, translucent members be-

hind said plates, a lamp within the casing, said lamp being mounted upon the cover and being removable therewith as a unit, electrical conductors within said casing and means for automatically effecting an electrical connection between said lamp and conductors whenever said cover is placed in operative position upon the casing.

4. An illuminated sign comprising in combination, a casing, a support therefor, said casing having a base and four corner posts spaced substantially equi-distantly from each other, said plates having indicia stamped therein and mounted on the corner posts, said plates being interchangeable, a cover mounted on the corner posts, a lamp mounted within the casing upon said base, a second lamp mounted within the casing upon said cover, electrical conductors extending alongside two of the posts, there being separable connections between said conductors and said cover, whereby the cover may be removed with the associated lamp as a unit from the casing and there being other separable connections between the conductors and the base whereby the casing may be removed as a unit from the base.

5. An illuminated sign comprising in combination, a casing, a standard therefor, said casing comprising a hollow box-like member mounted endwise on the standard, there being two lamps within said casing, a removable cover mounted on the top of the casing and providing a support for one of said lamps, the other of said lamps being mounted adjacent the opposite end of the casing, said lamps being connected to a common source of electrical supply, means for intermittently actuating said lamps, and a slip connection in circuit with said lamps for enabling the cover, together with the associated lamp, to be removed as a unit from the casing.

In testimony whereof, I hereunto affix my signature.

ARTHUR C. ARENDT.
